LOCKED BOX

Robert M. Lackey, Cohoes, N. Y.

Application March 12, 1932. Serial No. 598,373

1 Claim. (Cl. 229—47)

Among the principal objects which the invention has in view are: to provide a box of simplified construction which may be locked in closed or service relation by a simplified means; to provide a locking means that may be quickly and readily installed; to provide a cover for a box which may not be removed therefrom until properly released.

In the drawings:

Figure 1 is a side edge view of a box having a cover constructed and arranged in accordance with the present invention, the cover being shown as in position to be installed in service.

Figure 2 is a bottom plan view of a box having inclined end sections disposed in a cover constructed and arranged in accordance with the present invention.

Figure 3 is a corner fragment of the same, the fragment being shown in closed or service relation.

Figure 4 is a longitudinal section of the box locked in service relation.

Figure 5 is a similar view of the box, being shown as having the cover partially removed.

Figure 6 is a cross section of the box, the section being taken as on line 6—6 in Figure 4.

As seen in the drawings, the box body 11 has outwardly flared ends 12. The sides 13 are preferably perpendicular to the bottom 14. The corners formed by the junction of the sides and ends are reinforced in any known and suitable manner. The tray-like body thus formed is covered in service by a cover having a top 15 and inwardly inclined ends 16. The ends 16 and the straight side 17 of the cover are connected at the junction of

three of the corners in any known and suitable manner. At one corner, the sides 16 and 17 are provided each at one end with outwardly turned edges 18. These edges are not connected until the cover is disposed upon the body and it is desired to lock the box. To accomplish this a small metal tube 19 is employed. This tube, as shown best in Figures 3, 4 and 6 fits over and pinches the outwardly turned edges 18. The tube 19 has sufficient resiliency and strength to permit the introduction of the edges 18 between the split edges of the tube, to be held thereby so that the several corners will not escape the grip of the tube and cannot in fact be drawn from the tube except lengthwise thereof. With the cover in position and the tube 19 engaging the edges 18, it will be observed that the box is completely locked, it being impossible to lift the cover from the body while the corner restrained by the tube 19 is closed.

I claim:

A box as characterized comprising a body portion having outwardly flared sides and a cover therefor having inwardly contracted sides to conform with the sides of said body portion, means for permanently uniting the corners of said body portion and three of the corners of said cover, and means for closing the free edges of the sides of said cover when in service, said means comprising outwardly turned edges and marginal ends on said sides of said cover, and a resilient tube for engaging, between the free sides thereof, said edges.

ROBERT M. LACKEY.
